GEORGE W. RAWSON, OF CAMBRIDGEPORT, ASSIGNOR TO HIMSELF AND MICHAEL HITTINGER, OF SOMERVILLE, MASSACHUSETTS.

Letters Patent No. 82,751, dated October 6, 1868.

IMPROVEMENT IN CUT-OFF FOR STEAM-ENGINES.

The Schedule referred to in these Letters Patent and making part of the same.

TO ALL PERSONS TO WHOM THESE PRESENTS MAY COME:

Be it known that I, GEORGE W. RAWSON, of Cambridgeport, in the county of Middlesex, and State of Massachusetts, have invented a new and useful Improvement in the Variable Cut-Off for Steam-Engines; and I do hereby declare the same to be fully described in the following specification, and represented in the accompanying drawings, of which—

Figure 1 denotes an elevation of a slide-valve and the interior of a steam-chest, as provided with my invention.

Figure 2 is a longitudinal and horizontal section of the same.

My present improvement has reference to the subject of Letters Patent, No. 70,743, dated November 12, 1867, and granted to myself and Michael Hittinger on an invention made by me.

In carrying out my former invention, I employed rotary valves on the cut-off. It has been found that they are objectionable on account of the noise generated by them when closing down upon their seats, such noise being similar to that made by the tappets of steam-engine valves.

In order to get rid of the noise, I employ, in the first place, slide-valves for the cut-off valves, and move each of them in one direction by a chain, and stop the movement in the opposite direction by another chain, and by an arrangement, as hereinafter described, I effect a steam-balance of the cut-off valves prior to the slide-valves being moved relatively thereto.

In such drawing, A denotes the steam-chest, and B the slide-valve thereof. Such steam-chest is to be furnished with ports of induction and exduction, $a' b'$, to communicate with the engine-cylinder and the exhaust-pipe thereof. The seat of each set of these ports is raised above the bottom, d' , of the steam-chest, or formed on a projection, c' , raised thereon, in manner as shown in fig. 2, the same being in order that the slide-valve B, just prior to a movement of the cut-off slide e , may pass over or beyond the edge of the seat c' , so as to cause steam from the chest to flow into the chamber, e' , of the valve B, and against the bars of the valve e , and thus balance the force by which the cut-off valve may be pressed down upon its seat.

The slide-valve, arranged on its seats as represented, is to be moved longitudinally back and forth by a rod, a , jointed to a connecting-rod, b , worked by an eccentric in the ordinary way. The slide-valve has two exhaust-chambers, $d d$, and two induction-chambers, $e' e$, arranged in it in manner as represented, each of the chambers, e' , being open to the cut-off valve e in manner as shown in fig. 2.

The two cut-off slide-valves $e e$ have rods or bars, $g g$, projecting from them in manner as represented, these rods being supported by and so as to be capable of sliding lengthwise in two projections, $h h$, extended from the slide-valve.

Encompassing and attached to each of the said rods or bars $g g$ is a helical spring, k , which, by pressure against the next adjacent projection h , operates to move the bar in a manner to close the cut-off valve.

Furthermore, each of the slide-bars g has a notch, l , for the reception of one of two pawls or latches, $m m$, which are hinged to the two projections $h h$, and are connected by a helical spring, n , affixed to arms $x x$ projecting from the pawls.

Between the two pawls, and affixed to a vertical slide-rod, o , is a pawl-tripper or cam, p , whose two lower edges are arranged at an obtuse angle with each other.

The rod, o , of the pawl-tripper is to be so applied to a steam-engine governor as to be raised and lowered by it, the same being so that as the speed of the engine or governor may be increased, the pawl-tripper may be depressed, it being raised when the speed may slacken.

A chain, r , connects each of the cut-off valves with the next adjacent projection h . Another chain, s , also connects the said valve with the rod. It is not necessary for the chains s to be connected with the rod o , as they may be fastened to a projection from the steam-chest.

The chain s , when strained tight, holds the cut-off valves stationary in order that the main valve may move

relatively thereto, so as to enable steam from the chest to flow through the cut-off valve and the main valve. The chain *r* holds the cut-off valve closed on the ports of the main valve under the pressure of the next adjacent spring *k*.

While the slide-valve *B* may be moving toward either end of the steam-chest, the chain *s*, when drawn taut, will bring its cut-off valve *e* to a stand-still. The slide *B* continuing to move, its ports will be opened, and the next adjacent pawl will catch into the notch of the slide-bar of the cut-off valve, and thereby hold the cut-off stationary relatively to the slide-valve, the ports of the slide-valve being open. During the next movement of the slide-valve, that is, in the opposite direction, the pawl last mentioned will be carried against the next adjacent inclined face of the tripper, and by it will be forced out of the notch, so as to enable the cut-off valve to be closed by the action of its spring.

In this manner, the two cut-off valves will be alternately operated, the closing of each upon the ports of the slide-valve being effected sooner or later as the position of the tripper may be varied by the governor.

Just before each of the cut-offs is brought to a stand-still by its chain, *s*, the slide-valve *B* will have moved toward the next adjacent end of the steam-chest, so as to carry a small portion of the passage *e'* a little beyond the seat-projection *c'*, and thus enable steam from the steam-chest to flow into the passage *e'*, and thereby effect a counter-pressure on the cut-off to balance the pressure, which otherwise would operate to force the cut-off so closely upon the slide-valve as to create great friction between the two, and materially increase the power required to move the slide-valve.

From the above, it will be seen that, instead of using stops, such as are marked *r s* in the drawings of the patent to which allusion has been hereinbefore made, and such as are therein shown as applied to the valve-seats, I employ, with the cut-off, chains to arrest their movements. These chains, when properly made, will make no noise of any consequence at the time of being drawn straight. Consequently, I herein make no claim to the subject or subjects as claimed in the aforesaid patent.

What I claim, is—

The arrangement and combination of the stopping-chains with the steam-chest, the sliding, main, and cut-off valves, the springs *k k*, the rods *g g*, the pawls or catches *m m*, and the tripper *p*, to be applied to a governor, the whole being to operate in manner as described.

Also, the arrangement of the valve-seat projections *c'*, or the equivalents thereof, in relation to the steam-chest *A*, the main and cut-off slide-valves *B e e*, the stopping-chains, the springs *k k*, the cut-off valve-rods *g g*, the pawls *m m*, and the tripper *p*, the whole being as specified, the valve-seat projections enabling the steam to effect the balancing of the cut-off valves, as explained.

GEO. W. RAWSON.
